IGNITION SYSTEM

William E. Brown, Anderson, Ind., assignor to
 General Motors Corporation, Detroit, Mich., a
 corporation of Delaware

Application February 25, 1948, Serial No. 10,657

1 Claim. (Cl. 315—77)

1

This invention relates to ignition apparatus for automotive vehicles and its aim is to circumvent theft of an automobile by one who uses a jumper which can be quickly connected to the coil and battery terminals of the ignition switch, thereby maintaining ignition operative although the switch may be locked in "Off" position. This object is accomplished by a specially constructed ignition switch whereby the ignition coil terminal of the switch will be connected with the battery terminal when the movable contact of the switch is in "On" position and will be connected, when the movable contact is in "Off" position, through a resistance to means connecting the ignition coil with the ignition timer contacts and the condenser which parallels the contacts.

Further objects and advantages of the present invention will be apparent from the following description, reference being had to the accompanying drawing, wherein a preferred embodiment of the present invention is clearly shown.

In the drawing the single figure is a wiring diagram of the present invention.

The switch 10 has a movable contact of triangular formation which when in the "On" position represented by the triangle 11 in dot-dash lines connects a terminal 12 directly with the storage battery B with a terminal 13 connected with the primary winding 20 of an ignition coil C and also with a terminal 14 for making connection with an instrument (not shown). When the movable switch contact 11 is in "Off" position, as represented by the dash line triangle 11', an extension 13a of the terminal 13 is connected with a terminal 15, which is connected through a resistance 16 with that end of the primary winding 20 which is directly connected with the ignition timer T. The timer T includes a contact 21 engaged by movable contact 22 carried by lever 23 pivoted at 24 and urged clockwise by a leaf spring 25 connected with the lever and with a terminal 26. The engagement of a cam 27 with a rubbing block 28 on the lever causes the contacts to separate when an ignition spark is required. A condenser 29 is connected with the terminal 26 and parallels the timer contacts. The secondary winding 30 of the ignition coil C is connected with the rotor 31 of the distributor D having terminals 32 to which sparking impulses are distributed by the rotor 31 so that sparking will occur at spark plugs 33 in recurrent sequence.

When the switch 10 is "Off," the movable con-

2

tact is in the position of 11', and the battery B is disconnected from the coil C and the engine cannot be started, although it may be cranked by a starting motor. If a thief, in an attempt to steal the car, bridges across the terminals 12 and 13 by a jumper 40, the ignition coil primary 20 will receive very little current from the battery B since both ends of the winding 20 are practically at the same potential, the only difference being 5 the voltage drop across the resistance 16 which prevents a direct short circuit of the battery in case the ignition timer contacts are closed. Furthermore the condenser 29 is so connected that it cannot discharge through the ignition coil even 10 though it had had a charge which might cause ignition. When the switch is closed, the discharge circuit for the condenser is through the resistance 16, terminal 15, terminal 13, jumper 40, terminal 12 and battery B to ground rather than 15 through the inductive primary winding 20. Ignition is not possible because primary 20 is practically short-circuited and the condenser 29 would not discharge through the primary 20.

While the embodiment of the present invention as herein disclosed, constitutes a preferred form, it is to be understood that other forms might be adopted, all coming within the scope of the claim which follows.

What is claimed is as follows:

- 30 30. An ignition system comprising a current source, an ignition coil having a primary coil and a secondary coil, a timer having a contact connected with one end of the primary coil and a contact connected with the source and engaged by the first mentioned contact, a condenser having a terminal connected with the first contact and a terminal connected with the source, a switch having a first terminal connected with the source, a second terminal connected with the other end of the primary coil and having a third terminal, a resistance connecting the third terminal with the primary coil end first mentioned, a movable contact of the switch which, when in "On" position, connects the first and second terminals and 35 which, when in "Off" position, connects the second and third terminals, whereby the primary coil ends are shunted through the resistance and connection of the first and second terminals while the switch is "On" will provide a path of condenser discharge through the resistance and bypassing the primary coil.
